UNITED STATES PATENT OFFICE

MARIE-LOUISE MAILLARD, NÉE GOUGIS, OF NOGENT-LE-ROY, FRANCE

DISPENSER FOR PULVERULENT OR PASTY SUBSTANCES

Application filed May 10, 1929, Serial No. 361,970, and in France May 11, 1928.

The invention has for its object a dispenser for pulverulent or pasty substances, such as face powder, powdered soap, soap paste and the like.

5 Prior devices for this purpose commonly comprise a container from which the pulverulent material may flow through small apertures formed in the upper or lid portion of the container. One great disadvantage inherent in constructions of this kind is that the material discharged through the apertures has a tendency to settle toward the periphery of the container, causing escape and loss of material when the powder puff is 10 manipulated to pick up the material.

15 The present invention has among its objects the overcoming of this drawback by providing the container with conveyer means for discharging the material through apertures positioned at the central portion of the closure for the compartment containing the pulverulent or other material, whereby the amount of material discharged through said apertures may be controlled and regulated.

20 25 The invention will be best understood from the following description when read in the light of the accompanying drawings of a specific embodiment of the invention selected for illustrative purposes, the scope of which invention will be more particularly pointed out in the appended claims.

In the drawings:—

25 Fig. 1 is a diametrical vertical section of a powder box constructed according to the invention;

Fig. 2 is a plan of the powder box, according to Fig. 1, with the lid open and the powder tray removed;

Fig. 3 illustrates a detail of the powder box according to Figs. 1 and 2;

Fig. 4 is a fragmentary view illustrating a modification of the powder box according to Fig. 1;

Fig. 5 is a plan view of the parts shown by Fig. 4; and

Fig. 6 is a fragmentary section corresponding to Fig. 1 showing a modification.

The powder box illustrated by Figs. 1 and 2 comprises a lower compartment 1 which 50 contains the pulverulent or other material

and is provided axially thereof with a vertically disposed conveyer screw 2 which at its lower end is rigidly fastened to the bottom wall of this lower compartment, so that when the latter is rotated relative to the upper compartment of the box the screw will act to raise and discharge material from said lower compartment into said upper compartment.

As shown, the device comprises an annular member 3 to which the lid 5 of the box is hingedly connected at 4. Carried by this annular member is a tray 22 having a peripheral flange 23 which snugly engages the inner walls of the annular member. As shown, the tray 22 forms the bottom wall of the upper compartment and the top wall of the lower compartment. Removal of the tray from engagement with the annular member 3 will permit the lower compartment to be charged with material, and in this sense the tray constitutes a removable lid for the lower compartment, said lid being normally held in position due to its snug fit with the annular member 3. The annular lateral wall of the lower compartment 1 at its upper edge is provided with an inturned annular flange 21 in engagement with a circular slot formed about the lower portion of the outer wall of the annular member 3 to permit said lower compartment to be rotated relative to the upper compartment.

Interiorly of the lower compartment 1 is a cylindrical casing 12 which surrounds the screw 2, this casing being secured to the annular member 3 in non-rotatable relation therewith by radial arms 9 secured to the under side of the annular member at 8. The tray 22 is provided with an axial opening which registers with the upper wall 10 of the casing 12, said upper wall being provided with orifices 11 for discharge of the material from the casing 12 to the upper compartment.

At its lower end the casing 12 is provided with one or more lateral openings to permit the pulverulent or other material in the compartment 1 to enter said casing. In the present embodiment of this invention but one of such openings is shown, and communicating with this opening is a scoop-shaped

part having a top wall 13, an outer wall 42, and a radial wall 19, there being no radial wall opposite the latter so as to provide an opening into which the material may be scooped as the casing 12 is rotated relative to the compartment 1. As shown, cooperating with the scoop-shaped part just referred to is a bell crank lever 16 pivotally supported on a shaft 15, which latter at its upper end is pivotally supported in one of the arms 9, and at its lower end is pivotally supported on the horizontal leg of an angle bracket 14 rigidly carried by said arm, the shaft 15 having a torsion spring 20 normally holding the bell crank lever in the position shown by Fig. 2 of the drawings. The bell crank lever, which is formed of spring material, has an arm 18 which enters the scoop-shaped part referred to, the outer end of the arm 18 being in closely adjacent relation to the inner side of the radial wall 19 of said member. The other arm 17 of the bell crank lever is in sliding contact with a strip 6 secured to the inner side of the annular walls of the lower compartment 1, this strip having inwardly projecting curvilinear portions 7 which serve as cams for swinging the arm 18 of the bell crank lever toward the casing 12 as the lower compartment 1 is rotated relative to the upper compartment, and serving both to guide the material toward the scoop-shaped part referred to and force the material caught by said scoop-shaped part into the interior of the casing 12, and thus feed it to the rotating screw 2.

In the modification of the invention shown by Figs. 4 and 5, the upper side of the top wall 10 of the casing 12 is preferably lined by a layer 25 of velvet, chamois, or the like, secured thereto in any convenient way as by tubular eyelets 27 extending through the orifices 11, and, if desired, secured to the overlapping edges of the wall 10 by a ring member 26.

In the modification of the invention shown by Fig. 6, the lid 5 is provided with a downwardly projecting part 29 adapted to lock with a part 30 carried by the annular wall of the lower compartment 1 so as to prevent rotation between the upper and lower compartments, it being observed that the lid 5 is hingedly secured to the annular member 3, which latter rotatably carries the lower compartment. By this construction the screw 22 cannot be rotated relative to the casing 12 when the lid of the box is closed.

Having now particularly described and ascertained the nature of my invention, what I desire to secure by Letters Patent is as follows:

1. A device of the character described having, in combination, a container having a relatively rotatable apertured closure part, and conveyer means within said container responsive to said relative rotation for dis-

charging pulverulent material from said container through the aperture of said closure part.

2. A device of the character described having, in combination, a container having a relatively rotatable apertured closure part, conveyor means within said container responsive to said relative rotation for discharging pulverulent material from said container through the aperture of said closure part, and means within said container responsive to said relative rotation for feeding said material to said conveyer means.

3. A device of the character described having, in combination, a container part having a relatively rotatable apertured closure part, a screw conveyer cooperating with the aperture of said closure part comprising a screw operatively carried in fixed relation to one of said parts and a casing for said screw operatively carried in fixed relation to the other of said parts, whereby relative rotation of said parts will cause said screw to discharge material from said container through the aperture of said closure part.

4. A device of the character described having, in combination, a container part having a relatively rotatable apertured closure part, a screw conveyer cooperating with the aperture of said closure part comprising a screw operatively carried in fixed relation to one of said parts and a casing for said screw operatively carried in fixed relation to the other of said parts, whereby relative rotation of said parts will cause said screw to discharge material from said container part through the aperture of said closure part, and means cooperating with said casing and responsive to said relative rotation for feeding material to said casing.

5. A device of the character described having, in combination, a container having a relatively rotatable apertured closure, a tubular casing carried by said closure in alignment with the aperture thereof and extending into said container, and a conveyer screw in said tubular casing carried by said container, whereby relative rotation between said container and its said closure will cause relative rotation between said tubular casing and conveyer screw for causing material in said container to be forced by said screw through the aperture of said closure.

6. A device of the character described having, in combination, a container having a relatively rotatable apertured closure, a tubular casing carried by said closure in alignment with the aperture thereof and extending into said container, a conveyer screw in said tubular casing carried by said container, whereby relative rotation between said container and its said closure will cause relative rotation between said tubular casing and conveyer screw for causing material in said container to be forced by said screw through the

aperture of said closure, and means cooperating with said tubular casing and responsive to said relative rotation for feeding material to said tubular casing.

7. A device of the character described having, in combination, a container having relatively rotatable upper and lower compartments separated by an apertured partition, the latter operatively carried in non-rotatable relation to said upper compartment, a tubular casing operatively carried in non-rotatable relation to said partition in alignment with the aperture thereof, said tubular casing extending into proximity with the bottom of said lower compartment and adjacent its lower end having a lateral opening, means operated by relative rotation between said upper and lower compartments for feeding material in said lower compartment into said tubular casing through said lateral opening, and a conveyer screw in said tubular casing carried in non-rotatable relation to said lower compartment.

8. A device of the character described having, in combination, a container having relatively rotatable upper and lower compartments, means responsive to said relative rotation for feeding material from said lower to said upper compartment, a lid for said upper compartment, and means operative upon closure of said lid for restraining said compartments against relative rotation.

In testimony whereof, I have signed my name to this specification.
